INVENTOR:

Edward P. Beach,
BY drawn by ATTY'S.

UNITED STATES PATENT OFFICE.

EDWARD P. BEACH, OF NEWARK, NEW JERSEY.

DESIGN FOR A BRACELET.

SPECIFICATION forming part of Design No. 19,877, dated October 29, 1889.

Application filed September 25, 1889. Serial No. 325,079. Term of patent 3½ years.

To all whom it may concern:

Be it known that I, EDWARD P. BEACH, a citizen of the United States, residing at Newark, in the county of Essex and State of New Jersey, have invented and produced a new and original Design for a Bracelet; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In said drawings, Figure 1 is an edge view of a bracelet or necklace embodying my design. Fig. 2 is a face or plan view of a section or portion thereof.

Similar letters of reference indicate like parts wherever they occur.

The two views are deemed sufficient to fully illustrate my design.

The leading features of my design consist in the peculiar configuration presented by the

inner and outer surfaces of the bracelet. When viewed from the inside or outside, both 25 being the same, the configuration is clearly shown in Fig. 2, the outer edges showing a series of curves A, terminating in a series of ovals B, interlacing with one another at the center. 30

What I claim is—

The design for a bracelet or necklace herein shown and described, comprising a double-looped surface of overlapping sections alike on both sides, having at the outer edges or 35 sides a series of curves A, terminating in a series of ovals B, interlacing with one another at and through the center, as set forth.

In testimony that I claim the foregoing I have hereunto set my hand this 16th day of 40 September, 1889.

EDWARD P. BEACH.
